UNITED STATES PATENT OFFICE.

EDWARD B. SHIELDS, OF TACOMA, WASHINGTON, ASSIGNOR TO TURTLE-BACK LOG BUNK AND CAR STAKE COMPANY, OF TACOMA, WASHINGTON, A CORPORATION OF WASHINGTON.

LOG-BUNK

1,060,952.

Specification of Letters Patent.

Patented May 6, 1913.

Original application filed March 25, 1912, Serial No. 686,006. Divided and this application filed January 9, 1913. Serial No. 741,017.

To all whom it may concern:

Be it known that I, EDWARD B. SHIELDS, a citizen of the United States, residing at Tacoma, in the county of Pierce and State 5 of Washington, have invented a new and useful Log-Bunk, of which the following is a specification.

This invention relates to bunks adapted to be mounted on a flat car and on which 10 logs may be piled, and has for its objects to provide a bunk which is very strong and stiff in form and thus capable of standing the strains developed when very large logs are rolled thereon in loading the car; which 15 reinforces the car body by distributing the strains across the entire width of the car; which has means for retaining and guiding a releasable stake at each end beyond the side sills of the car, thus making the full 20 width of the car available for logs; which prevents the accumulation of dirt, bark, snow or ice in any way which would interfere with the free action of the stakes; and which protects the car from being damaged 25 by a log being unloaded.

Another object of my invention is to provide improved means of mounting the bunk on the car whereby the sills of the car are tied together across the car and are kept 30 from spreading under the heavy loads and the strains across the car are carried to the sills; and whereby the bunk is secured to the sills without making any holes therein which would weaken them.

I attain these and other objects by the devices, forms and arrangements illustrated 35 in the accompanying drawings, in which—

Figure 1 is a perspective view of the bunk showing a portion of one side sill under one end thereof; Fig. 2 is a vertical longitudinal section of one end of the bunk; Fig. 3 is a side elevation thereof; Fig. 4 is a plan thereof; and Fig. 5 is a cross-section thereof.

Similar numerals of reference refer to similar parts throughout the several views.

The bunk illustrated in the drawings and described herein is the same as that illustrated in my application for Letters Patent for car stakes, Serial No. 686,006, March 25, 1912 and this application is divided out from the said application.

The main body of the bunk 1 is formed as shown in section in Fig. 5, of an in-

verted-U or high arch shape, having substantially parallel and vertical sides 2, joined on top by a substantially semicircular arch 3, but being entirely open at the bottom. At each end of the bunk the arched portion is projected outward along an inclined line so that the end of the bunk near the crown is several inches beyond the foot of the bunk. The said extensions are however not completed to the crown of the arch but each has a slot 4 formed in the crown, 65 said slots running inward from the ends and being adapted to receive the above mentioned car stake with the radius arm thereof. A pair of vertical flanges 5 extend down from each side of said slot, one flange having its outer edge vertical and extending inward therefrom to the end wall 6 which closes the end of the bunk; the other flange being similar except that an outward extending shoulder 7 is formed thereon. The 75 said flanges 5 form the guide walls for the said stake. The end wall 6 extends only from each flange 5 to the walls 2 and arch 3 of the bunk but not between the two flanges.

The two flanges 5 extend down below 80 the level of the base of the bunk so as to form a bracket to engage the outer side of the side sill 8 of the car, and are joined together below the top of the sill 8 by a web 9, thus forming a very strong and stiff bearing plate or bracket whereby the inward side pressures on the bunk are transferred to the sill and whereby the two side sills are tied together and thus reinforced. Holes 10 are made in the end walls 6, through which the 85 bar of the stake on the opposite side passes as described in the above mentioned application. A pair of brackets 11 extend out from the lower edge of the side walls 2 near each end of the bunk, being adapted 90 to support the end of the releasing lever of said stake bar as described in said application.

The bunk is supported by the lower edges of the side walls 2, having bearing flanges 100 12 and 13 extending out from the said walls at the points where they bear on the side or intermediate sills of the car respectively. One end, bearing flange 12 extends a short distance out from the sill while the one on 105 the other side of the bunk extends a similar distance inward. These two extensions have bolt holes therethrough. A pair of bolts

14 pass through the said holes and through holes in the ends of a clamp plate 15 which engages the lower side of the sill 8, lying diagonally beneath it. One of said bolts 14 5 lies against the inner side of the sill while the other similarly engages the outer side thereof. The bunk is therefore held on the sill by the bolts without making any holes in the sills or in any way weakening them. 10 It will therefore be seen that the vertical depth of the walls and arch give this bunk great strength. The weight and strains from the log, which lies directly upon the arch of the bunk, are transmitted to the car 15 through the arched portion and separated walls of the bunk which distribute the strains evenly across the car. The arch sinks slightly into the bark of the log thus holding it from a too free movement end- 20 wise thereon. The fact that the base is open between the separated vertical walls prevents the accumulation of refuse which might interfere with the free operation and control of the stakes, and this effect is fur- 25 ther enhanced by the fact that the top is entirely closed against such refuse except at the end slots which are occupied by the stakes. The fact that the bunks themselves extend out beyond the sides of the car is of 30 great practical value since the sides are thus protected from damage from the logs when they are being unloaded and further it gives the free use of the entire width of the car for logs. The novel method of attaching 35 the bunk on the car is also of value as it reinforces the car without weakening the sills by bolt holes. The bunk is preferably made of cast steel being integral throughout.

40 Having described my invention what I claim is:—

1. A device of the class described comprising a bunk extending across the car and having a semicylindrical top adapted to receive logs.
2. A device of the class described comprising a bunk extending across the car and having a semicylindrical top adapted to receive the logs, and an open bottom where- 50 by no dirt is retained therein.
3. A device of the class described comprising a bunk extending across the car and having two vertical parallel walls, joined by a semicylindrical top integral there- 55 with and adapted to receive the logs.
4. A device of the class described, com-

prising a bunk extending across the car and having two vertical parallel walls, separated at their base, but joined together by a semi-cylindrical top integral therewith and adapt- 60 ed to receive the logs.

5. A device of the class described, comprising a bunk extending across the car and having a semicylindrical top adapted to receive the logs, and having extensions to 65 the ends of said arched top to protect the sides of the car.

6. A device of the class described, comprising a bunk extending across the car and having a semicylindrical top adapted to receive the logs, and having bifurcated ex- 70 tensions to the ends of said arched top to receive a log retaining means.

7. A device of the class described, comprising a bunk extending across the car and 75 having two vertical parallel walls coextensive with the width of the car, joined by an arched top integral therewith and adapted to receive the logs, said arched top having bifurcated ends extending beyond the 80 sides of the car to receive a log retaining means.

8. A device of the class described, comprising a bunk extending across the car and having brackets extending downward from 85 its ends and engaging the sides of the car, and an arched top adapted to receive the logs.

9. A device of the class described, comprising a bunk extending across the car 90 and having brackets extending downward from its ends and engaging the sides of the car, and having vertical parallel walls joined by an arched top integral therewith and adapted to receive the logs.

10. In a device of the class described, the combination with a bunk extending across the car; flanges formed on the bottom of said bunk and extending outward therefrom, said flanges being positioned to extend in pairs beyond the inner and outer sides of the side sills respectively; clamp plates adapted to engage the lower surfaces of the said side sills and extending beyond them; and bolts passing through said clamp plates and said flanges on each side of each of said side sills whereby said bunk is clamped to said sills. 95 100 105
